United States Patent Office.

WILLIAM H. FLINN, OF NASHUA, NEW HAMPSHIRE, ASSIGNOR TO HIMSELF AND ALBERT H. SAUNDERS, OF SAME PLACE.

Letters Patent No. 75,745, dated March 24, 1868.

IMPROVED MEDICINE-BOTTLE.

The Schedule referred to in these Letters Patent and making part of the same.

TO ALL PERSONS TO WHOM THESE PRESENTS MAY COME:

Be it known that I, WILLIAM H. FLINN, of Nashua, of the county of Hillsboro, and State of New Hampshire, have invented a Bottle or Vessel for Holding, Measuring, and Administering Medicine; and I do hereby declare the same to be fully described in the following specification, and represented in the accompanying drawings, of which—

Figure 1 is a side view, and

Figure 2 a vertical section of it.

In carrying out my invention, I combine with the cork or stopper, A, of a bottle, B, a small glass open vessel or cup, C, which I attach by or at its bottom, to the bottom of the cork or stopper, and so as to extend within the bottle when the stopper is therein. This vessel is open at its lower end like a tumbler. If desirable, it may have one or more marks or divisions made on its surface to indicate the measure of an amount of liquid when in the cup.

To use the cup, the cork or stopper is to be withdrawn from the bottle and inverted, so as to bring the cup uppermost. The cup will then be ready to receive a quantity of the liquid or medicine which may be in the bottle, which may be poured from the bottle into the cup, after which the medicine may be introduced into the mouth of a person by means of the cup.

The medicine-administering bottle so made will be found very useful to physicians, or various other persons.

I do not claim a cup arranged in the top of a stopper of a bottle.

I claim the arrangement of the cup with the stopper, so that when the latter is within the neck of the bottle, the cup will extend into the bottle, as specified.

WM. H. FLINN.
